UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

SURFACE-CONTACT RAILWAY SYSTEM.

SPECIFICATION forming part of Letters Patent No. 735,584, dated August 4, 1903.

Application filed April 23, 1902. Serial No. 104,274. (No model.)

To all whom it may concern:

Be it known that I, WILLIAM B. POTTER, a citizen of the United States, residing at Schenectady, county of Schenectady, State of New York, have invented certain new and useful Improvements in Surface-Contact Railway Systems, of which the following is a specification.

My invention relates to electric railways operated by the well-known closed-conduit or surface-contact system, and constitutes an improvement on the system shown and described in Patent No. 589,786, granted to me September 7, 1897.

The object of my invention is to provide a system of the character shown in the patent above referred to with a metallic return-feeder so arranged and connected that while substantially all the return-current will be conducted back through it to the generating-station no substantial difference of potential can exist between it and ground.

My invention consists in providing an electric-railway system with a metallic return-feeder, which metallic return is grounded at a point remote or at the end of the feeder most distant from the source of energy, but which is elsewhere insulated from the ground.

By the use of a ground connection at the end of the negative feeder farthest from the source of energy the advantages of a metallic return system, such as obviating the requirement of rail-bonding and preventing the electrolytic action on water and gas pipes, which are necessary evils connected with the grounded track-rail return, are obtained, while at the same time the buttons or contacts, which are normally connected with the negative feeder, have their potential maintained at the potential of the ground, which eliminates all liability of injury to life and limb from energized negative conductors in the roadway and obviates the necessity of placing switches between the negative studs or conductors and the feeder.

The accompanying drawing shows diagrammatically a surface-contact system embodying the features of my present invention.

In the figure, A A represent the track-rails, on which the wheels R R of the car operate. B, B', B², and B³ are the studs which are

connected to the positive feeder P through the switches G G' G², &c. The studs C, C', and C² are connected with the negative main N through the operating-coils of the switches G G' G², &c., while the studs D, D', and D² are connected directly with the negative main N, which is grounded at g at the end farthest from the source of energy S. The collector-shoes carried by the car are designated by F, F', and F². The shoe F is connected with the motor M of the car through the controller-switch s' and resistance r', and the return from the motor M is connected with the shoe F. The battery E or auxiliary source of power carried by the car which is used temporarily to pick up the switches when starting the car is connected across the outside shoes F and F² and is connected in series with the switch s and the resistance r.

The operation of the system is as follows: The switch G is picked up at first by a current which flows from the auxiliary source of power E, carried by the car through the switch s, resistance r, shoe F, contact-stud C, actuating-coil of switch G, contact-stud D, shoe F², back to the source of power E. When the switch G has been closed in this manner, the switch s is opened and the switch G is maintained in its closed position by current from the feeder P flowing through the switch G, contact-stud B', shoe F', resistance r', motor M, shoe F, contact-stud C, actuating-coil of switch G', to negative feeder N. As the car moves forward the advance switch G' is closed by current from the shoe F flowing through the contact-stud C', actuating-coil of switch G', to negative feeder N, thus energizing the advance stud B² and maintaining the contact-stud B' energized after the switch G has been opened. The return-feeder N being connected to ground at its farther end, none of the contacts D D', &c., can ever be at a potential substantially different from that of ground, and hence they may be with perfect safety permanently connected to the return-feeder.

While I have shown and described a surface-contact system embodying my invention, I do not limit myself to such a system, since my invention would be equally applicable to a sectional third-rail system using a

metallic return-circuit and to other well-known systems.

What I claim as new, and desire to secure by Letters Patent of the United States, is—

5 1. In an electric railway, a source of energy, a positive and a negative feeder leading from the same, and a ground connection at a single point, said point being at the end of the negative feeder farthest from the source 10 of energy.

2. In an electric railway, a source of energy, a sectional conductor, switches for connecting the sections of said conductor successively with the said source, an insulated 15 return-conductor, and a single ground connection for said conductor, said ground connection being made at a point remote from the said source of energy.

3. In an electric railway, a source of energy, a positive and a negative feeder connected therewith, a sectional conductor connected to said positive feeder, switches in said connections, a sectional conductor connected with said negative feeder, and a single ground 25 connection for said negative feeder, said ground connection being made at a point remote from the source of energy.

4. In an electric railway, a source of energy, a positive and a negative feeder leading 30 from the same, a sectional conductor connected to said positive feeder through electromagnetic switches, a sectional conductor permanently connected to said negative feeder through the respective coils of said electromagnetic switches, and a single ground 35 connection for said negative feeder, said ground connection being made at a point remote from the source of energy.

5. In a surface-contact system, a source of energy, a positive and a negative feeder leading from the same, a plurality of sectional working conductors, electromagnetic switches for connecting said sectional conductors to said positive feeder, a plurality of sectional switch-energizing conductors independent of 45 said working conductors, electrical connections between said switch-energizing conductors and said negative feeder, and a single ground connection for said negative feeder, said ground connection being made at the end 50 farthest from the source of energy.

6. In a surface-contact railway, a source of energy, a positive and an insulated negative feeder connected therewith, positive sectional conductors, electromagnetic switches for establishing temporary connection between the positive feeder and the successive positive sectional conductors, each switch provided with a single actuating-coil, negative sectional conductors, permanent electrical connections 55 each including one of said actuating-coils between said negative feeder and said negative sectional conductors, and contacts making direct connection between the positive feeder and the positive sectional conductors, each 60 switch furnishing current to more than one sectional conductor, and a single ground connection for said negative feeder, said ground connection being made at the end farthest from the source of energy.

In witness whereof I have hereunto set my hand this 21st day of April, 1902.

WILLIAM B. POTTER.
